DESIGN FOR A GLASS

Jeddia B. Clark, Dunkirk, Ind., assignor to Indiana Glass Company, Dunkirk, Ind., a corporation of Indiana

Application October 5, 1935, Serial No. 58,844

Term of patent 7 years

To all whom it may concern:

Be it known that I, Jeddia B. Clark, a citizen of the United States, residing at the city of Dunkirk, in the county of Jay and State of Indiana, have invented a new, original, and ornamental Design for a Glass, of which the following is a specification, reference being had to the accompanying drawing, forming a part thereof.

Figure 1 is a side elevational view of the article, showing my design;

Figure 2 is an inverted plan view of the bottom portion of the glass;

Figure 3 is a transverse section taken on the plane of the line 3—3 of Fig. 1;

Figure 4 is a transverse section taken on the line 4—4 of Fig. 1;

Figure 5 is a fragmentary vertical sectional view taken on the lines 5—5 of Figs. 1 and 2;

Figure 6 is a fragmentary, vertical sectional view taken on the line 6—6 of Fig. 1.

I claim:

The ornamental design for a glass, as shown and described.

Dated at Dunkirk, Indiana, this 26th day of September A. D. 1935.

JEDDIA B. CLARK.
